UNITED STATES PATENT OFFICE.

VOJTECH PUC, OF PRAGUE-WEINBERGE, CZECHOSLOVAKIA.

PRESS BUTTON.

Application filed September 24, 1926, Serial No. 137,568, and in Czechoslovakia November 19, 1925.

In press-buttons of a known type, in which springs are provided in the upper or female part and the cap of the upper part has a tubular extension for riveting over, it may happen that, when being riveted to the fixing washer, the pressure applied in riveting may make the slots for guiding the springs narrower, so that, after the upper part of the press-button attached to the fabric has been removed from the punch used in riveting, the springs can no longer enter the slots. This renders the upper part of the press-button useless, as the opening in the cap is no longer capable of being constricted yieldingly by the springs. This results in a great many throw-outs being made.

The object of the present invention is to overcome this difficulty. The invention consists substantially in this, that above the slots 20 provided for receiving the springs the wall of the cap is weakened. This weakening which may for instance be effected by reducing the thickness of the wall of the cap or by cutting away portions of the wall, has the effect that the pressure exerted in riveting cannot be propagated as far as the slots of the springs and is limited to the compression of the weakened part of the cap.

The slots for the springs thus always retain their dimension required for giving the springs the necessary play.

In the accompanying drawing two constructional examples of the upper part of the press-button are shown,

The left hand part of Figure 1 being a longitudinal section through one constructional form of the upper part of the press-button before being riveted to the fixing washer and the right hand part of the figure 40 being a longitudinal section of the upper part of the press-button after it has been fixed to the material.

Fig. 2 is a longitudinal section through a plane at right angles to that of the section in Fig. 1, and

Fig. 3 a second constructional form of the upper part of the press-button in longitudinal section.

The upper part of the press-button shown in Figs. 1 and 2 consists in a known manner of the cap 1 which is provided with the flange 9 and to which is connected the hollow rivet 2 the diameter of which is reduced so as to form the projecting annular shoulder 8. The cap is provided with the slots 3 for the reception of the springs 4. When rivet-

ing the upper part of the press-button for the washer 5 with the material 6 between the said washer and the flange 9, it has hitherto been necessary to keep the cap 1 supported by its annular shoulder 8 resting on the lower die 7 of the riveting press and for the flange 9 of the upper part of the press-button to be at a certain distance from the part 10 of greater diameter of the lower die. Only in this way was it possible to prevent the slots 3 of the cap from being compressed through the pressure used in riveting so that the springs 4, after removing the upper part of the press-button from the riveting die 7 could engage freely in the slots 3.

As it may occur that for instance the axial dimension of the riveting die 7 may change owing to wear and that the cap will consequently no longer be supported by the die 7 against the pressure exerted in riveting, so that the flange 9 rests immediately on the part 10 of the die, according to the present invention slots 11 are provided in the cap part above the slots 3.

The riveting pressure, on being applied, will act on the upper part of the cap 1, which has been weakened by the slots 11, so that the material of the cap will only be compressed in this part, until the annular shoulder 8 rests on the die 7. The slots 3 will on the other hand have remained unaltered, thus ensuring that the springs 4 will engage properly with the slots after the riveting has been completed.

As will be readily seen, the invention makes it possible for the cap part to merge directly in the hollow rivet, thus doing away with the annular shoulder 8 so that a straight, cylindrical or conical wall 12, 12', 12'' is obtained (Fig. 3). By weakening the material above the slots 3 for the springs it is only necessary for the lower die 7 to enter into the cap as far as is necessary for securing its central position on the upper die of the riveting press. A further advantage is that the upper part of the press button is easier to make without the annular shoulder 8.

What I claim is:

1. For use in a press button fastener, a socket part having a tubular extension capable of being riveted over for securing the socket part in position, slots in the said socket part and springs in the socket part extending through the said slots for engaging with a stud part, weak places in the wall

of the socket part above the said slots for the springs, as and for the purpose set forth.

2. For use in a press button fastener, a
6 socket part having a tubular extension capable of being riveted over for securing the
socket part in position, slots in the said
socket part and springs in the socket part
extending through the said slots for engag-
10 ing with a stud part, slots in the wall of the
socket part above the said slots for the
springs, as and for the purpose set forth.
3. For use in a press button fastener, a
15 socket part having a tubular extension capable of being riveted over for securing the
socket part in position, slots in the socket
part and springs in the socket part ex-
tending through the said slots for engaging
20 with a stud part, said tubular extension be-
ing constructed to form a smooth continua-

tion of the wall of the socket part and weak
places being provided in the said wall of the
socket part above the said slots for the
springs, as and for the purpose set forth.

4. For use in a press button fastener, a
25 socket part having a tubular extension capable
of being riveted over for securing the
socket part in position, slots in the said
socket part and springs in the socket part
extending through the said slots for engag-
30 ing with a stud part, said tubular extension
being tapered and forming a smooth continua-
tion of the wall of the socket and weak
places being provided in the wall of the
socket part above the said slots for the
35 springs, as and for the purpose set forth.

In testimony whereof I have signed my
name to this specification.

VOJTECH PUC.
